UNITED STATES PATENT OFFICE

JULIUS B. WANTZ, OF CHICAGO, ILLINOIS; ASSIGNOR TO VICTOR ELECTRIC COMPANY, OF CHICAGO, ILLINOIS, A CORPORATION OF ILLINOIS.

TERAPEUTIC LAMP.

No. 870,262.

Specification of Letters Patent.

Patented Nov. 5, 1907.

Application filed March 9, 1907. Serial No. 361,425.

To all whom it may concern:

Be it known that I, JULIUS B. WANTZ, a citizen of the United States, residing at Chicago, in the county of Cook and State of Illinois, have invented a new and useful 5 Improvement in Therapeutic Lamps, of which the following is a specification.

My invention relates to improvements in the class of therapeutic lamps in which the illuminating medium—
as an incandescent electric lamp—is combined with a 10 reflector arranged to direct the light-rays, for their therapeutic effect, against parts of the body of a patient under treatment.

The primary object of my invention is to provide a multiple lamp in the class referred to, of novel construction adapting it to afford the advantages herein-after stated; and a further object is to provide simple and novel means for supporting the lamp by suspension, whereby it shall be adapted to be readily adjusted to any desired angle for directing the light-rays.

20 In the accompanying drawings, Figure 1 shows my improved therapeutic lamp by a view in side elevation; Fig. 2 is a top plan view of the same; Fig. 3, a bottom plan view of a disk-shaped coupling-head upon which to make electrical connections of the lamps with the 25 conductor-wire for supplying current thereto; Fig. 4, a section taken at the line 4 on Fig. 2 and viewed in the direction of the arrow, and Fig. 5, a section taken at the line 5 on Fig. 2 viewed in the direction of the arrow and enlarged.

30 The base 6 is a metal plate 7, preferably of disk-shape and having a highly polished under surface to adapt it to reflect light-rays, with a post 8 rising from its center, about which are formed hood-seating openings, 9, 10, 11, 12; and a metal flange 13 extending circumferentially about the plate and preferably flaring outwardly from its edge, the inner surface of the flange being also highly polished to adapt it to reflect light-rays.

35 In the openings 9 to 12, inclusive, are seated at their wider beaded ends, respectively, hoods 14, 15, 16 and 40 17, all being of like construction. Each is of preferred general cone-frustum shape with its apex removed and having formed about its apical end a perforated heat-ventilating collar 18, on which is mounted a socket 19 for an incandescent electric lamp 20 inserted into it 45 from within the hood, which surrounds it, the socket having connected with it a conducting-wire 21 terminating in a plug 22 of insulating material containing metal-lined sockets 23, 24. The inner surfaces of the hoods are highly polished to cause them to reflect the

50 light from their contained lamps through the openings in which they are seated, and which dispose the four hoods in pairs at right-angles to each other. Three of the hoods are shown to be permanently fastened on the base 6, by suitable clips 25 engaging their beaded edges, 55 three of these clips so fastening each hood, except the

hood 17, which is fastened by only two clips 25, and by a slotted finger 26 releasably engaging the beaded hood-base, being secured in place by a set-screw 27 passing through its slot into the plate 7. By loosening the set-screw and withdrawing the finger from engagement with the respective hood-base, the hood 17 is released and may be withdrawn from the clips 25 overlapping its beaded edge, to enable this hood to be used separately, for the purpose hereinafter stated. To facilitate manipulation of the removable hood it is provided with a handle 28, shown as projecting from the collar 18.

The post 8, which is tubular, is fastened rigidly in place by a rod 29 passing through an opening in the center of the plate 7 and having a head 30 on its lower end at which it engages the plate about the opening; 70 the rod being threaded at its upper end where it passes through a disk-head 31 of insulating material, as hard rubber, which seats on the post 29 and is fastened by a nut 32 screwed upon the rod to also fasten the post. An outer conducting-wire 33, forming an electric connector, is secured, to describe a partial circle, to the under surface of the head 31, by screws 34 at and between its ends, and an inner conductor 35, like the conductor 33, is similarly fastened by screws 34 to said head-surface. Pairs of rigid, longitudinally-split coupling-pins 37, 37, fastened by screws, extend upward through the head, the members of the pairs being thus connected, respectively, with the wires 33 and 35, and each pair is adapted to enter the sockets of a plug 22, which is frictionally held upon them by compressing 80 their split resilient sections. In this way each lamp 20 may be readily coupled to current-supply wires 38 and 39, which lead through holes 40 in the head, respectively, to a depending binding-post 41 engaging the connector 33 on the head 31 and a similar binding-post 90 42 engaging the connector 35. The wires 38 and 39 are formed into a cable 43, provided on its end with a plug (not shown) of the usual kind for insertion into the socket of an incandescent-electric-lamp fixture; and it affords the medium of suspension of my improved 95 therapeutic lamp, from a hook (not shown), which may be fastened in the ceiling of the room in which the lamp is used, to adapt the cable to be looped about it. For hiding the mechanism on the under side of the head 31, an ornamental cup 8¹ is confined against it on the 100 post 8.

On the base 6, near the edge, is rigidly fastened an arm 44 terminating in a circular head 45 with a screw-stud 46 projecting centrally and laterally from it. Against the head 45 is adjustably confined, by a thumb-nut 47 engaging the stud, the perforated head 48 of a bent arm 49 terminating at its free end in an eye 50, at which it engages a hook 51 depending from the collar 52 provided about the lower end of the cable 43. By setting the arm 49 to extend at any desired angle from the 111

rigid arm 44, the center of gravity of the base 6 may be changed to cause it to hang at any angle at which it is desired to face its reflecting surfaces.

The multiple construction thus described enables all 5 or fewer than all of the lamps on the base to be used at the same time, according to requirement in the matters of heat-regulation and light-diffusion, since to cut in or out any lamp its plug 22 may be readily adjusted on or separated from the pins 37; and the disposition of the 10 lamps in pairs at right-angles to each other permits either pair to be used for covering with the light elongated surfaces. Moreover, the removable quality of the one hood adapts it for independent application for certain purposes requiring only its light, or heat, or 15 both.

What I claim as new and desire to secure by Letters Patent is—

1. In a therapeutic lamp, the combination with a base-plate provided with a plurality of hood-seating openings 20 arranged in pairs at right-angles to each other, hoods seated in said openings and having inner reflecting surfaces, lamps supported in said hoods, separable electrical connections for said lamps whereby various light combinations can be obtained and means connected with the base 25 plate for flexibly suspending said lamp from a support.
2. In a therapeutic lamp, the combination of a base-plate provided with a plurality of hood-seating openings, a hood seated non-removably in one of said openings and a hood removably seated in another of said openings, said 30 hoods having inner reflecting-surfaces, lamps supported in said hoods, and means connected with the base-plate for flexibly suspending said lamp from a support.
3. In a therapeutic lamp, the combination of a base-plate provided with a plurality of hood-seating openings, a 35 hood seated non-removably in one of said openings, a hood removably seated in another of said openings, said hoods having inner reflecting-surfaces, a handle on said removable hood, lamps supported in said hoods, and means connected with the base-plate for flexibly suspending said 40 lamp from a support.
4. In a therapeutic lamp, the combination of a base comprising a plate with a flange extending about it, having an inner reflecting surface, said plate containing a plurality of hood-seating openings, hoods seated in said openings and having inner reflecting surfaces, and lamps supported in said hoods.
5. In a therapeutic lamp, the combination of a base-plate provided with a plurality of hood-seating openings, hoods seated in said openings and having inner reflecting-surfaces, lamps supported in the hoods, means connected 50 with the base-plate for flexibly suspending it with the parts upon it, and a device for adjusting the angle of suspension, consisting of a rigid arm on said plate and an arm adjustably connected with said rigid arm and engaging 55 with the flexible suspending medium.
6. In a therapeutic lamp, the combination of a base-plate provided with a plurality of hood-seating openings, hoods seated in said openings and having inner reflecting-surfaces, lamps supported in the hoods, a flexible suspending medium connected with said plate and having a hook, and means for adjusting the angle of suspension, consisting 60 of a rigid arm on said plate provided with a screw stud, an arm pivotally supported on said stud and having an eye in its free end at which it engages said hook, and

a nut working on said stud for fastening said arms together in their adjusted relation.

7. In a therapeutic lamp, the combination with a base-plate provided with a plurality of hood-seating openings, hoods having inner reflecting-surfaces seated in said openings and provided with electric-lamp sockets, electric-lamps supported in said sockets within the hoods, flexible conductors extending from said sockets and provided on their outer ends with coupling plugs, a conductor for supplying current for said lamps, electric connecting means adapted to have coupled thereto said plugs, and means connected with the base plate for flexibly suspending said lamp from a support.

8. In a therapeutic lamp the combination with a base-plate provided with a plurality of hood-seating openings, 80 hoods having inner reflecting-surfaces seated in said openings and provided on their ends with electric-lamp sockets, electric-lamps supported in said sockets within the hoods, flexible conductors extending from said sockets and provided on their outer ends with coupling-plugs, a conductor for supplying current for said lamps, a head carrying connector wires, binding posts extending from said wires to which the conductor is attached, and pins extending from said wires to be engaged by said coupling-plugs.

9. In a therapeutic lamp, the combination of a base-plate provided with a plurality of hood-seating openings, 90 hoods, having inner reflecting-surfaces, seated in said openings and provided with electric-lamp sockets, electric-lamps supported in said sockets within the hoods, flexible conductors extending from said sockets and provided on their outer ends with coupling-plugs, a post rising from 95 said plate, a head on said post provided with electric connecting means adapted to have coupled thereto said plugs and the conductor for supplying current to said lamps, and means connected with the base-plate for flexibly suspending said lamp from a support.

10. In a therapeutic lamp, the combination of a base-plate provided with a plurality of hood-seating openings, hoods having inner reflecting-surfaces seated in said openings and provided on their ends with electric-lamp sockets, electric-lamps supported in said sockets within the hoods, 100 flexible conductors extending from said sockets and provided on their outer ends with coupling-plugs, a post rising from said plate, a head on said post carrying on its under-side connector-wires, binding-posts extending from said wires and adapted to have connected with them the conductor for supplying current to said lamps, and pins extending from said wires to be engaged by said coupling-plugs.

11. A multiple therapeutic lamp comprising, in combination, a base consisting of a plate with a circumferential outwardly-flaring flange, having inner reflecting-surfaces, said plate containing a plurality of hood-seating openings, hoods seated non-removably in certain of said openings and a handle-equipped hood removably seated in another of said openings, means on said base for releasably fastening said removable hood in place, said hoods having inner reflecting-surfaces, electric-lamp sockets on the hoods, electric-lamps supported in said sockets within the hoods, flexible conductors extending from said sockets and provided on their outer ends with coupling-plugs, a post rising from said plate, and a head on said post provided with electric coupling means for said plugs and with binding-posts at which to connect wires for supplying current to the lamps.
